UNITED STATES PATENT OFFICE.

JOHN B. SEMPLE, OF SEWICKLEY, PENNSYLVANIA.

PERCUSSION-FUSE FOR SHELLS.

SPECIFICATION forming part of Letters Patent No. 790,401, dated May 22, 1905.

Application filed June 6, 1904. Serial No. 211,242.

To all whom it may concern:

Be it known that I, JOHN B. SEMPLE, of Sewickley, Allegheny county, Pennsylvania, have invented a new and useful Percussion-5 Fuse for Shells, of which the following is a full, clear, and exact description, reference being had to the accompanying drawings, forming part of this specification, in which—

Figure 1 is a sectional side elevation of my 10 improved fuse with the parts in unarmed position. Fig. 2 is a similar view showing the parts in armed position after firing. Fig. 3 is a side elevation, partly broken away, showing a modification with the parts in unarmed 15 position; and Fig. 4 is a side elevation, partly broken away, showing the form of Fig. 3 with the parts in armed position.

My invention relates to the class of percussion-fuses for explosive shells, and is designed 20 to provide a simple and effective construction by which the firing-pin may be moved from unarmed position into the armed position and locked in such position by the act of firing.

In the drawings, referring to the forms of 25 Figs. 1 and 2, 2 represents the fuse-stock, which may be of any desirable construction and contains a cylindrical cavity the interior rear wall of which is preferably provided with a central flat plane portion 3, from which the 30 conical surface 4 leads to the side wall of the cavity.

The firing-pin 5 rests within a central hole leading through the plunger 6 and is normally held in unarmed position by a frangible 35 pin 7 extending through registering holes in the plunger and pin. The rear end portion of the plunger is provided with a lip 9, which is preferably annular in shape and surrounds the rear portion of the firing-pin body, which 40 has a rear projection 8 thereon. 10 indicates the cap-socket, which is secured within the crimped lip 11 of the fuse-stock and contains the percussion cap or detonator 12.

The fuse is secured within the rear end of 45 the shell by interfitting screw-threads or other suitable connection, the parts then being in the position shown in Fig. 1.

Upon firing, the fuse-stock and firing-pin are driven forward relatively to the plunger, which is momentarily held by its inertia.

During this relative forward movement the beveled or conical face 4 contacts with and crimps the lip 9 of the plunger around the shoulder between the rear end of the firing-pin body and its reduced extension 8 after 55 the movement of the fuse-stock has broken the frangible pin 7 and then driven the firing-pin forwardly in the plunger. The parts then take the armed position shown in Fig. 2, and upon the impact of the shell the firing-pin 60 explodes the percussion-cap in the usual manner by the forward movement of the pin and plunger relative to the fuse-stock. It will be noted that when in unarmed position the plunger is locked to the firing-pin in one 65 relative position by the frangible cross-pin, while upon firing the positions of the plunger and firing-pin are shifted and the firing-pin is then locked to the plunger in armed position with the firing-pin point projecting 70 beyond the forward end of the plunger.

Instead of making the projection 8 as a part of the firing-pin it may be formed as a part of the rear wall of the fuse-stock cavity. Thus in Figs. 3 and 4 I show a construction 75 similar to that of the first form except that the firing-pin 5 is of the same diameter throughout its length and the rear wall of the fuse-block cavity is provided at its center with the projection 8', which acts to move 80 the firing-pin forwardly within the plunger-hole to a position where the lip 9' is crimped over the rear end of the firing-pin by the action of the conical or beveled face 4'. The operation of this form is substantially that 85 of the first form, the frangible pin being broken upon firing and the firing-pin then locked to the plunger in its projected position by the crimping of the plunger-lip around its rear end.

The plunger and firing-pin are preferably 90 made of the same metal or alloy, such as brass, and the same material may be used for the fuse-stock and cap-socket.

The advantages of my invention result from 95 the forcing forward of the firing-pin relative to the plunger by the action of the fuse-stock upon its rear end and the locking of the firing-pin to the plunger in its new and armed position by crimping or bending in a portion

of the plunger to prevent rearward movement of the firing-pin relative thereto when in armed position. A simple and effective construction is thus afforded which will give positive action, especially in smaller shells, such as one-pounders. The firing-pin is normally held in unarmed position by the frangible pin, while the beveled or conical face of the fuse-stock cavity acts to bend in the rear lip portion of the plunger to lock the pin in its new position.

The same fuse may be used as a point-fuse by providing a passage-way for the flash of the primer to the rear and reversing the position of the fuse-stock. The form of the pin and plunger may be varied and any desirable type of fuse-stock and cap may be used without departing from my invention.

I claim—

1. In a percussion-fuse, a fuse-stock having a cavity, a plunger within the cavity, a firing-pin, a projection between the rear end of the firing-pin and the fuse-stock, and means for crimping the rear portion of the plunger around the rear portion of the firing-pin when the firing-pin is moved into armed position; substantially as described.

2. The combination with a fuse-stock having a cavity, of a plunger therein, a firing-pin within the plunger and secured in unarmed position by a frangible pin, a projection between the fuse-stock and the rear end of the pin, and means for crimping a portion of the plunger around the normally projecting rear end of the firing-pin when the parts are driven into armed position; substantially as described.

3. The combination with a fuse-stock having a cavity, of a plunger therein, a firing-pin within the plunger and normally locked thereto in unarmed position, a projecting lip at the rear end of the plunger, and means for crimping said lip around the rear end of the firing-pin as the parts are driven into armed position; substantially as described.

4. The combination with a fuse-stock having a cavity, of a plunger therein, a firing-pin within the plunger and normally locked thereto in unarmed position, a projecting lip at the rear end of the plunger, and a beveled or inclined face on the rear wall of the fuse-stock cavity constructed to crimp the lip around the rear end of the firing-pin as the parts are driven into armed position; substantially as described.

5. The combination with a fuse-block having a cavity, of a plunger in the cavity and having a rear lip, a firing-pin normally held in unarmed position within the plunger by a frangible connection therewith, a projection between the rear end of the firing-pin and the rear wall of the fuse-stock cavity, and an incline at the interior rear wall of the cavity constructed to crimp the lip around the rear end of the firing-pin as the parts are driven into armed position; substantially as described.

In testimony whereof I have hereunto set my hand.

JOHN B. SEMPLE.
